UNITED STATES PATENT OFFICE.

LOUIS ANDREWS, OF ARKANSAS CITY, ARKANSAS.

DIVISION-PLATE FOR OIL-PRESSES.

SPECIFICATION forming part of Letters Patent No. 296,105, dated April 1, 1884.

Application filed September 17, 1883. (No model.)

To all whom it may concern:

Be it known that I, LOUIS ANDREWS, a citizen of the United States, residing at Arkansas City, in the county of Desha and State 5 of Arkansas, have invented new and useful Improvements in Division-Plates for Oil-Presses, of which the following is a specification.

This invention relates to certain improvements in division-plates used in presses for extracting oil from cotton-seed; and the said invention consists in details of construction of said plates whereby a more perfect extraction of the oil is effected, the use of the costly hair mats now employed to hold the meal is dispensed with, and the oil is prevented from being reabsorbed into the cake after once being expressed therefrom.

Referring to the drawings forming part of this specification, and in which similar letters of reference indicate like parts in the several views, Figure 1 represents a plan view of one of the plates for oil-presses constructed according to my improvement, a portion of the thin perforated corrugated copper plate being removed to show the corrugations in the main plate; Fig. 2, a longitudinal section of a portion of the plate; Fig. 3, a side elevation or edge view of a portion of the plate, showing the holes or drains for the oil. Fig. 4 represents an end view of a portion of the press-stand, showing two plates in position therein, one being in section. Fig. 5 represents an end view, showing the grooved plates placed upon each other; and Fig. 6, a sectional detail of the same.

C C are the press-plates, having along the top edge at each side vertically-projecting flanges D D, which extend the whole length of the plate. The bottom portions of these plates are so formed—that is, with a projecting portion, C', of a width relatively to the space between the flanges D—that the said bottom C' will fit close between the said flanges D in the pressing action. A lateral extension is formed along each side of these press-plates, as at E, into which is formed gutters or channels A A, extending longitudinally and having vertical openings H. The top, as also the bottom, surface of these press-plates are corrugated or formed with curved depressions c and elevations c', which extend transversely across the surface of the plates, but do not extend to or

abut against the vertical side flanges, D, a space, d, being left between the ends of the 55 corrugations and the inner sides of the flanges, the object of which will hereinafter appear. At the bottom of the depressions c, across the face of the plates C, are formed shallow channels, which extend entirely across the width of 60 the plates and through the side vertical flanges, D, and open just above the gutter A, as shown at F in Figs. 3 and 4. Transversely through the vertical flanges D, near the top edge thereof, is formed a series of small holes, G, and at 65 intervals along the channel A are vertical openings H through the plates. K are guide ears or lugs, which, partially embracing the standards or pillars L of the press, hold the plates in their proper relations.

B is a sheet of No. 16 copper plate, corrugated so as to fit close upon the face of the corrugated press-plate C, between the flanges D, and having a series of perforations, b, therein, arranged in transverse lines across said plate, 75 and in such position relatively to the depressions c in the press-plate as to come over the channels F. Because of the bottom extension, C', of the plates C, fitting between the flanges D in the top of the next lower plate, the liability to break is avoided, should nothing be placed between any two plates or unusual pressure bring two plates together. The faces of the plates also being parallel, any amount of pressure may be applied without danger, 85 and being parallel, an equal pressure is exerted on all parts of the cake or body of material in the press, a uniform size and shape is, therefore, given to it, which is an important matter. The rear back end of each division-plate is constructed with a cross-rib, I, on its upper side, which extends above the top surface of said plate, and the bottom of said plate has a corresponding cross-recess, I', at 90 its rear edge, which, when the plates are in position to press the mat, receives the top rib, I, and, while serving to prevent the escape of the oil at this point, serves as a stop or limit for the insertion of the material between the press-plates, thereby preventing the too far 95 insertion of the material upon the plate. The object of the perforated copper sheet is to permit the ready passage of the expressed oil from the meal, but at the same time prevent the entrance of the meal in the channels or 100 drains F. The top and also the bottom sur- 105

face of the press-plates being corrugated to correspond one with the other, their surfaces are on a horizontal line and flush one with the other. An equal pressure is therefore exerted 5 at all points upon the mass.

The operation is as follows: When the press is lowered for receiving meal, the plates part about three inches, and the meal, after having previously been inclosed in woolen cloth 10 and formed into a cake in a preliminary press, is placed upon a proper-shaped piece of sheet-iron and thrust between the press-plates, and then the sheet-iron removed, the side flanges, D, and end cross-rib, I, acting as guides and 15 enabling the workman to properly place the meal-sack. Upon applying the pressure, the oil, as it is expressed from the meal, passes into the several drains and is conducted where desired. The oil from the bottom of the cake, 20 passing through the perforations *b* in the copper plate, enters the transverse channels *F* and escapes into the side gutters, *A*. The oil from the top of the cake finds an escape through the drains *G*, through the flanges *D*, 25 and also enters the gutters *A*, from whence it is conducted through drains or openings *H* to the storage-tank. By reason of the corrugations not extending entirely across the press-plates to the side flanges, *D*, the meal is prevented 30 from spreading, and because of the corrugated perforated sheet *B*, the clogging of the drains *F* is prevented and the quick escape of the oil is permitted; also, by reason of this perforated plate, the cake is separated 35 from the oil, and therefore reabsorption of the oil by the cake is prevented when the pressure upon said cakes shall have been withdrawn. The cake is therefore delivered in a compact dry state, and of a uniform size and 40 thickness throughout its mass.

Referring to the drains *A F G*, for the oil, at the top of the plate, it will be noticed that they are on different levels, and that the two upper ones open into the side gutters 45 through the side flanges *D D* of the press-plate *C*. It will also be noticed that by constructing the press-plate as described it forms a complete device, requiring no special construction of oil-mat, but allowing of the use 50 of a woolen sack only to inclose the substances or cake.

I claim—

1. In a press for extracting oil from cotton-seed meal or other substance, the herein-described division-plate *C*, constructed with the corrugations *c c'*, top side flanges, *D D*, and top side gutters, *A*, outside of said flanges, the cross-depressions *c* in the top of the plate opening into shallow-bottom drain-channels *F*, which, 60 extending across the plate at the bottom of said depressions, open through said side flanges, *D*, into the side channels, *A*, and the said side flanges having drains *G*, opening above said corrugations *c* into said side gutters, whereby 65 the oil is drained from the said division-plate through its side flanges, *D D*, both from the top and from the bottom of the cake while un-

der compression, substantially as shown and described.

2. In a press for extracting oil from cotton-seed meal and other substances, the division-plate *C*, constructed with top side flanges, *D* 70 and bottom extension, *C'*, the latter being adapted to fit within the former when the plates are brought together, substantially as 75 shown, and for the purpose described.

3. In a press for extracting oil from cotton-seed meal and other substances, the division-plate *C*, constructed with top side flanges, *D* 80 and bottom extension, *C'*, the latter being adapted to fit within the former when the plates are brought together, the top and bottom surfaces of said division-plate being formed with cross-corrugations, the drains *F* 85 *G* and the side gutters, *A*, on the upper side of said plate being arranged at different levels, all constructed substantially as shown and described.

4. In a press for extracting oil from cotton-seed meal and other substances; the division-plate *C*, constructed with top cross-corrugations, *c c'*, the top side flanges, *D D*, the drains 90 *F G*, and the side gutters, *A*, in combination with a copper sheet, *B*, formed with cross-corrugations corresponding with those in the 95 division-plate, and having perforations *b*, arranged in line over the cross drain-channels *F*, whereby said copper plate forms a permanent corrugated seat for the mat, conforming 100 to the corrugations of the division-plate, substantially as described, for the purpose specified.

5. The combination, in a press for extracting oil from cotton-seed meal and other substances, of the division-plate *C*, constructed 105 with top and bottom cross-corrugations, the top side flanges, *D D*, the top drains, *A G F*, and the bottom extension, *C'*, the latter adapted to fit within the former when the plates are brought together, with a permanent perforated copper sheet, *B*, conforming to the 110 corrugations in the top and bottom of the division-plates, forming a mat-seat placed within and between the said side flanges, whereby the plates will match with solid surfaces on a 115 level when brought together, as shown and described.

6. The herein-described division-plate, constructed with top side flanges and a bottom extension, the latter adapted to fit between 120 the former when the plates are brought together, the cross-corrugations in the top and bottom surfaces, the top drains, *A G F*, and the top end cross-rib, *I*, joining the said side flanges, *D D*, whereby to form a stop to limit 125 the placing of the sack of meal upon said plates, as shown and described.

In testimony whereof I have hereunto set my hand in the presence of two subscribing witnesses.

LOUIS ANDREWS.
